(57) **CLAIM**

The ornamental design for a fire pit, as shown and described.

DESCRIPTION

FIG. 1 is top perspective view of a first embodiment of a fire pit shown in an environment of use;
FIG. 2 is a bottom perspective view thereof;
FIG. 3 is a top perspective view of a first embodiment of a fire pit shown separately for clarity of disclosure;
FIG. 4 is a bottom perspective view thereof;
FIG. 5 is a left side elevation view thereof;
FIG. 6 is a right side elevation view thereof;
FIG. 7 is a front elevation view thereof;
FIG. 8 is a back elevation view thereof;
FIG. 9 is a top plan view thereof;
FIG. 10 is a bottom plan view thereof;
FIG. 11 is a top perspective view of a second embodiment of a fire pit shown in an environment of use;
FIG. 12 is a top perspective view of a second embodiment of a fire pit shown separately for clarity of disclosure;
FIG. 13 is a bottom perspective view of a second embodiment of a fire pit shown in an environment of use;
FIG. 14 is a bottom perspective view of a second embodiment of a fire pit shown separately for clarity of disclosure;
FIG. 15 is a left side elevation view thereof;
FIG. 16 is a right side elevation view thereof;
FIG. 17 is a front elevation view thereof;
FIG. 18 is a back elevation view thereof;
FIG. 19 is a top plan view thereof; and,
FIG. 20 is a bottom plan view thereof.

(Continued)

The broken lines illustrate portions of the fire pit that form no part of the claimed design.
